PRINTING TELEGRAPH EXCHANGE SYSTEM

Jackson C. Fricke, Brooklyn, N. Y., assignor, by
mesne assignments, to International Standard
Electric Corporation, New York, N. Y., a corpo-
ration of Delaware

Application July 21, 1930, Serial No. 469,393

19 Claims. (Cl. 178—4.1)

This invention relates to printing telegraph exchange systems and more particularly to a printing telegraph exchange system in which the lines extending between the central station and the subscriber's stations are normally open to direct current.

Heretofore in printing telegraph exchange practice there have been systems in which the lines extending between the central station and the subscribers' stations or subscribers' lines are normally open to direct current, while the lines are closed, when intercommunication between the central station and the subscriber's station is to take place, by manual means at the subscriber's station. Such systems required an attendant operator at each subscriber's station for the purpose of closing the subscriber's line to direct current whenever the central station desired to communicate with the subscriber's station. In the present system, the subscribers' lines are normally open to direct current, but in place of the manual means at each subscriber's station for closing the line to direct current, means under control of the control station are provided for closing the line whenever intercommunication between the stations is desired. Once the subscriber's line has been closed, the printing telegraph apparatus at the subscriber's station is automatically conditioned for the reception of messages, thus making it unnecessary for the subscriber's operator to be in attendance whenever it is desired to transmit a message from the central station to the subscriber's station.

One of the principal objects of the present invention is to eliminate in a printing telegraph exchange system the current drain which ordinarily takes place over the lines extending between the central station and the several subscribers' stations.

Another object is to provide means at the central station for automatically closing the line to direct current and for automatically conditioning the printing telegraph apparatus at each of the stations for intercommunication.

In carrying out the objects of the invention, an alternating current relay is associated with the line at each of the subscribers' stations and a source of alternating superimposed on direct current is provided at the central station, and when these sources are impressed upon the line, the alternating relay at the connected subscriber's station is operated, closing the line to direct current and conditioning the telegraph apparatus for intercommunication.

One embodiment of the present invention is

shown in the accompanying drawing which represents diagrammatically the various circuits, relays and other equipment arranged in three groups which are respectively designated O, the operating table, C, the concentration board, and S, the subscriber's station.

At station S a signaling button 1 is grounded on one side through a resistance 2 and on the other side connects with the line 3. An alternating current relay 4 is adapted to respond to a revertive signal which results from plugging in a cord tip at the concentration board C. Two pairs of contacts 5 and 6 are closed by the actuation of relay 4, and after the latter has been tripped by a signal, it remains mechanically locked, until released by an associated slow operating restoring relay 7. A condenser 8 is placed in the circuit of the relay 4 to make the latter responsive only to A. C. signals and to prevent current drain from battery 21 during idle periods. A retard coil 9 is placed in the circuit of the relay 7 to assist in slowing up its operation. A slow release relay 10 is included in the communication circuit between two printers. It is adapted to hold open the restoring relay circuit and also to maintain a closed printer motor circuit during the transmission of messages. When a plug is removed from its jack at the concentration board the slow release relay 10 is deenergized and restores the subscriber's station to normal or idle condition.

The printer motor 11 is shown in a circuit 12 which connects with any suitable A. C. or D. C. power source. The printer magnet 13 is in series with the printer keyboard circuits 14.

At the concentration board C of the central office the subscriber's line 3 is shown connected through an adjustable resistance 15 with a monitor jack 16 and thence to a regular jack 17. The line circuit is then conducted to one coil of a line relay 18, through the contact springs 19 of a slow release relay 20 and thence to a grounded battery 21.

A line lamp 22 connects through the resistance 23 with the grounded battery 24 and also with the contact point 25, adapted to be connected to a grounded armature of relay 18. Relay 18 is controlled by relay 20.

A locking circuit 26 for relay 18 includes a winding thereon, one terminal of which connects with its own locking contacts 27. This circuit also includes the breaker contacts 28 under the control of relay 20.

A cord-tip circuit 29 connects any jack at the concentration board C with suitable instruments

at the operating table O. A supervisory lamp circuit 30 includes two lamps 31, one at the concentration board C and the other at the operating table O.

5 The cord-sleeve circuit 57 is conducted through the winding of a relay 32 which has the following functions, (1) to put battery potential on the line relay 33, (2) to complete the operating circuit for the printer motor 34, (3) to close a circuit for 10 revertive signalling to the subscriber's station, and (4) to prepare a locking circuit for the relay 35 which serves momentarily to transmit the revertive signal and afterwards maintains a closed circuit between the operating table printer-key- 15 board 36 and the cord-tip circuit 29.

The revertive signalling circuit 37 has impressed upon it both alternating and direct current sources 38 and 39 respectively. The line relay 33 is provided with a biasing circuit 40. Its 20 armature circuit receives potential from the battery 41 which is conducted to the printer magnets 42 and also to the coil of a supervisory relay 43. The circuit for relay 43 is not completed, however, unless the operator pushes the button 44 to 25 signal the concentration board operator that the message transmission has been completed. In doing this, the supervisory relay is actuated to open the supervisory lamp circuit 30. The line relay 33, the printer magnets 42, and the transmitter 36 are normally disconnected from the loop section 29, but are connected thereto upon the operation of ring and trip relay 35.

The operation of this invention will now be explained. It will be assumed that a message is 35 to be transmitted from station S to the central office O. The subscriber depresses the push button 1 thus grounding the line relay circuit which may be traced from battery 21 through the contact springs 19 of relay 20, through the operating 40 winding of line relay 18, through the short-circuited contact springs of jacks 17 and 16 respectively and thence through resistance 15 and line 3 to push button 1 which is grounded through the resistance 2. The line relay 18 operates to 45 establish a monitor line lamp circuit which may be traced from battery 24 through the resistance 23, lamp 22, to ground through the armature and contact 25 of relay 18. This lamp is lighted to signal the operator at the concentration board. 50 Another pair of contacts 27, of the line relay 18 operate to ground a locking circuit through this relay, current being supplied from the battery 21 through the break contacts 28 of relay 20 and through the conductor 26 which includes the locking 55 winding of relay 18.

Upon seeing the lighted line lamp, the supervisor inserts in the line jack 17 a cord plug associated with an idle printer. The plug-tip 48 breaks the circuit through the line relay 18 and the plug sleeve completes a circuit through the winding of the slow release relay 20. This circuit may be traced from battery 21 through the winding of 60 relay 20, through the jack sleeve 17, the plug sleeve and the cord circuit 51, and the relay winding 32 to ground. The slow release relay 20 and cord circuit relay 32 both operate, the former opening the circuits to the line relay winding 18, restoring that relay to normal and extinguishing the line lamp 22; the latter applying direct 65 current potential to the printer motor 34 and also to the line relay 33 and the transmitting keyboard 36. This latter circuit, however, is not completed through the line 3 until relay 35 operates to draw its armature against contact 51. Previous to 70 this, a revertive signalling circuit upon which both

alternating and direct current sources 38 and 39 respectively are superimposed, is established by relay 32. This circuit may be traced through the conductor 37, contacts 46, one of the windings of relay 35, contact 47 and armature of said relay, 5 cord-tip circuit 29, the tip thereof 48, jack contact 49, line 3, condenser 8, relay contacts 50 and alternating current relay 4 to ground.

As soon as this relay 4 is actuated, contacts are made between the pairs of springs 5 and 6 respectively. This allows the direct current to follow through the circuit just described as far as the station-S-terminal of line 3 and thence through contact 5 to winding of relay 10 from which it continues through the printer magnet 13 and key- 15 board 14 to ground.

As the left hand armature 58 of relay 10 starts to pull up it is momentarily grounded through a make-before-break spring combination 59. This has the effect of accelerating the operation of 20 relay 10 since the inductive resistance of the printer magnet 13 is by-passed. At the same time relay 35 is energized drawing its right-hand armature against the contact 51. This completes the circuit from the operating table keyboard 36 to 25 the line. Furthermore, a locking circuit is established through relay 35, originating at the battery 52 and passing through the locking contacts 53, winding 54, contact 45 of relay 32 and the armature 55 thereof which is grounded. The breaking 30 of contact 47 interrupts the circuit whereon alternating and direct current sources 38 and 39 respectively are superimposed. At the subscriber's 35 station the relays 4 and 7 are arranged for co-operation so that when relay 4 operates its armature is mechanically locked by a latch 58. This locking arrangement holds the contacts 5 and 6 in the "make" position until the locking arrangement is tripped by the relay 7.

The operation of relay 10 closes the circuit 40 12 from a source of power through the printer motor 11. In order to obviate any chance of the relay 7 operating and breaking the line circuit prematurely, the retard coil 9 is placed in 45 series with its winding so that before it can pull up the slow release relay 10 operates and cuts off the battery 56 from relay 7.

The circuit is now in condition for printer 50 operation and it will be understood that the printer signals do not release the slow release relay 10 because there is no interruption in the flow of current through traffic transmission of sufficient duration to allow said relay 10 to release.

To terminate a call, the operator at the central 55 offices depresses the bush button 44 thus operating and locking up a supervisory relay 43 and extinguishing supervisory lamps 31. The concentration board supervisor withdraws the plug from the jack 17 which restores all circuits to 60 normal at stations O, C and S respectively. The slow release relay 20 at the concentration board is timed to allow the slow release relay 10 at the subscriber's station to release first supplying current from battery 56 to relay 7 and 65 operating the relay. This in turn restores contacts 5 and 6 to their "open" position. During the restoration operation, the circuit to relay 4 is broken by relay 7 so that a capacity kick from the line cannot operate it. When contacts 6 have 70 been opened, relay 7 deenergizes, the slow release relay 20 at the concentration board now releases and all circuits are restored to normal. It is evident that the operation of the system 75 is the same as that just described when a call 75

is initiated at the central office, except that in this case the line relay 18 and the supervisory lamp 22 at the concentration board are not operated.

5. What is claimed is:

1. A telegraph system comprising a first station, a second station, a line normally open to direct current connecting said stations, telegraph apparatus at each of said stations normally disconnected from said line, a source of alternating current at said first station, an alternating current relay at said second station, responsive to the connection of said source to said line, for connecting the telegraph apparatus at said second station to said line, and means responsive to the operation of the alternating current relay for connecting the telegraph apparatus at said first station to said line.

2. A printing telegraph system comprising a first station, a second station, a line normally open to direct current connecting said stations, a printer at each of said stations normally disconnected from said line, a motor for operating each of said printers, means under control of said first station for closing said line to direct current for connecting the printer at each of said stations to said line and for starting the printer motor at each of said stations.

3. A printing telegraph system comprising a first station, a second station, a line normally open to direct current connecting said stations, a printer at each of said stations normally disconnected from said line, an operating motor associated with each of said printers, a source of alternating current at said first station, an alternating current relay at said second station responsive to current from said source when the latter is connected to said line for connecting the printer at said second station to said line, means thereafter operable for starting the printer motor at said second station, and means for starting the printer motor at said first station prior to the connection of the printer at said second station to said line.

4. A printing telegraph system comprising a first station, a second station, a line normally open to direct current connecting said stations, a printer at each of said stations normally disconnected from said line, an operating motor for each of said printers, a relay at said first station, an alternating current relay at said second station, responsive to current from said source when the latter is connected to said line, for connecting the printer at said second station to said line, and means responsive thereto for starting the motor at the second station and for operating said first station relay to connect the printer thereto to said line.

5. A printing telegraph exchange system comprising a first station, a second station, a line connecting said stations, a printer at each of said stations normally disconnected from said line, a source of alternating current at said first station, an alternating current relay at said second station, responsive to current from said source when the latter is connected to said line, for connecting said printers to said line, and means for disconnecting each of said printers from said line.

6. A printing telegraph system comprising a central station, a source of alternating current at said station, a sub-station, a line normally open to direct current connecting said stations, a printer normally disconnected from said line, a motor control relay and printer motor at said

sub-station, means controlled by said central station for closing said line to direct current and for connecting said printer and motor control relay to said line, and means thereafter operable for actuating said motor control relay to close the operating circuit of said printer motor.

7. A printing telegraph system comprising a central station, a sub-station, a line normally open to direct current connecting said stations, a printer and a motor control relay normally disconnected from said line, and a motor for operating said printer at said sub-station, means controlled by said central station for closing said line to direct current and for connecting said printer and motor control relay to said line, and means thereafter operable for actuating said motor control relay to close the operating circuit of said motor.

8. A printing telegraph exchange system comprising a central station, a sub-station, a line normally open to direct current connecting said stations, said sub-station having a printer and a motor control relay normally disconnected from said line, a motor for operating said printer and an alternating current relay for conditioning said line to permit the flow of direct current and for connecting said printer and motor control relay to said line, means at said central station for operating said alternating current relay, and means thereafter operable for actuating said motor control relay to start said motor.

9. A printing telegraph exchange system comprising a central station, a source of alternating current superimposed upon a source of direct current at said station, a sub-station, a line normally open to direct current connecting said stations, said sub-station having a printer and a motor control relay normally disconnected from said line, a motor for operating said printer, an alternating current relay, responsive to alternating current from said source when the latter is connected to said line, for connecting said printer and motor control relay to said line, said motor control relay being responsive to direct current from said source, after the closure of said line to direct current, to start said printer motor.

10. A printing telegraph exchange system comprising a central station, a source of alternating current at said station, a sub-station, a line normally open to direct current connecting said stations, said sub-station having a printer and a motor control relay normally disconnected from said line, said motor control relay having one circuit through said printer and an additional bypass circuit, a motor for operating said printer, a slow-operating restoring relay for re-opening said line to direct current, and an alternating current relay, associated with said line and operated by current from said source when the latter is connected to said line, for connecting said printer and said motor control relay to said line and for closing an operating circuit for said restoring relay, and means thereafter operable for energizing said motor control relay over said bypass circuit before the restoring relay is operated, whereupon said printer motor is started and the operation of said restoring relay is prevented.

11. A printing telegraph exchange system comprising a central station, a sub-station, a line normally open to direct current connecting said stations, said sub-station having a printer and a motor control relay normally disconnected from said line, a motor for operating said printer, and an alternating current relay operable from said central station for closing said line to direct
